ABSTRACT

A power piston actuates a series of link members which are pivotally interconnected and which are also pivotally connected to the rotor hub and the blade so that actuation of the power piston will actuate said links to cause said blade to move to its folded position and to be locked in the folded position due to a link over-center condition.

FIG. 5

HELICOPTER BLADE FOLDING AND LOCKING MECHANISM

BACKGROUND OF THE INVENTION

1. Field of the Invention

This invention relates to the folding of helicopter blades and more particularly to the folding of helicopter blades wherein the blades are locked both in their folded and in their unfolded positions and wherein the folded blades so locked require no external force to maintain the fold lock.

2. Description of the Prior Art

In the helicopter blade folding art, folding mechanism have been used in which gear sectors are actuated to cause blade folding and unfolding, and separate link sets serve to hold the blade in the fully folded position. These gear mechanisms not only require intricate machining but must be adjusted for back-lash. In addition, the sliding surfaces of the gear faces must be kept lubricated to reduce wear on these surfaces. Further, the separate links must be periodically adjusted because of the wear on the sector gears.

Other types of blade fold mechanisms use complicated series of links and cams, most of which are located externally of the blade and hub and are therefore vulnerable to breakage in use and by firearms, corrosion damage besides being complicated in nature and are aerodynamically unsound.

SUMMARY OF THE INVENTION

A primary object of this invention is to provide an improved blade fold and lock mechanism in which the blade is both folded and locked by a simple link mechanism.

In accordance with the present invention, the entire blade folding and locking mechanism is located internally within the blade or hub so that it is protected thereby from damage due to external forces.

In accordance with a further aspect of the present invention, the links are of a selected length and orientation to fit the fold angle and over-center requirements, and best provide, within the limits of practicality, a maximum folding moment about the fold pin at the points of maximum blade resistance to folding and unfolding of the blades.

In accordance with still a further aspect of the present invention, apparatus is provided to control the degree of folding of the blade and to positively stop the power piston when the blade is in its fully folded condition.

In accordance with still a further aspect of the present invention, the folding links go into over-center relationship when the blade is in its fully folded position and so remain when hydraulic power is removed from the power piston.

In accordance with still a further feature of the present invention, the blade is folded about a fold pin having an axis forming a selected angle with the blade feathering axis and with the blade plane of rotation so as to safely and selectively control the path of the blade during the folding operation and to selectively position the blade in the desired fully folded position, while maintaining adequate clearance from the ground, fuselage, and other blades during the folding operation.

Other objects and advantages of the present invention may be seen by referring to the following descrip-

tion and claims, read in conjunction with the accompanying drawings.

BRIEF DESCRIPTION OF THE DRAWINGS

FIG. 1 is a plan view of my blade folding and lock mechanism in its rotor head environment, partially broken away to reveal the folding and locking mechanism in the blade operating or unfolded position.

FIG. 2 is a side view of my blade fold mechanism in the blade operative or unfolded position, partially in cross section.

FIG. 3 is a plan view of my blade fold mechanism in the blade folded position.

FIG. 4 is a schematic representation of the blade fold pin and its axis with respect to the blade feathering axis and the rotor plane of rotation.

FIG. 5 is a graphic representation of blade fold motion for three selected conditions.

FIG. 6 is a partial showing of my invention in a second type of rotor head.

DESCRIPTION OF THE PREFERRED EMBODIMENT

Referring to FIGS. 1 and 2 we see my blade fold mechanism in its helicopter rotor environment in its blade unfolded or operating position. As best shown in these figures, helicopter rotor 10 comprises rotor hub 12 which is mounted for rotation about axis of rotation 14 and helicopter blade 16, which is one of a series of identical blades projecting from hub 12 for rotation therewith about axis 14 so as to create lift. Blades 16 are mounted from hub 12 so as to be rotatable about feathering axis 18 through the action of pitch change horn 20, which is controlled by conventional pitch change control mechanism (not shown). Blade 16 is connected to hub 12 through fold hinge 15 and through sleeve 22, which generally envelops the blade fold and lock mechanism 30. There is one such mechanism 30 for each blade of different fold angle and both the 30 blades and their blade fold and lock mechanism which may be identical, but not necessarily so due to different clearance problems around the aircraft.

Blade 16 is pivotally connected to fold hinge 15 through fold pin 17 to permit blade folding and to sleeve 22 and hence hub 14. As best shown in FIG. 4, the axis 19 of fold pin 17 forms a selected angle with respect to both the plane of the blade feathering axis 18 and the rotor plane of rotation 21 so as to permit the blade to follow a selected path during the folding and unfolding motion and to assume a selected position when fully folded so as to avoid all obstacles, including the ground, the fuselage, and other blades, during the folding and unfolding motion and so as to nest selectively with the other blades, fuselage, or the like when in the fully folded position.

The significance of the compound angle of axis 19 of fold pin 17 depicted in FIG. 4 is best understood by viewing FIG. 5 in which line 51 represents the blade operational or zero degree fold positions and line 53 represents the blade fully folded position. Line 55 represents the path of a blade when blade folding axis 19 does not form an angle to the feathering axis plane or the rotor plane. The result of blade fold motion along line 55 would be interference between the various blades during the blade folding and unfolding operation. Line 57 represents the path when a blade which has selected angular relationship with the blade feath-

ering axis plane only and not with the plane of the rotor. While blades following path 57 would not interfere with one another, the maximum downward vertical displacement of the blade, which would be encountered at the blade 90° fold angle, would exceed the minimum required ground clearance and therefore the blade would possibly strike the ground during blade folding and unfolding operation. Line 59 is the path of blade fold when the angular relationship shown in FIG. 4 exists between the blade fold pin axis and both the rotor plane and the feathering axis plane. It will be noted that blade path 59 provides increased ground clearance during the blade folding and unfolding operations and therefore avoids the blade striking the ground, however, the final vertical blade displacement is the same, and therefore the blade fully folded nesting position is the same for blade paths 57 and 59.

While FIGS. 1-3 illustrate my blade fold and lock mechanism 30 in the environment of a particular rotor head, it should be noted that as best shown in FIG. 6, my blade fold and lock mechanism 30 is also usable with a conventional sleeve and spindle rotor head of the type shown in U.S. Pat. No. 3,097,701, wherein the piston and crank or link mechanism would be mounted within the spindle and rotation between the spindle and sleeve would be taken out by a selfaligning bearing at 52.

Still viewing FIGS. 1 and 2, we see that blade fold and lock mechanism 30 includes linkage assembly 32, which is powered by power cylinder-piston arrangement 34, which includes piston member 36 positioned within cylinder 38 and with provisions for either air or hydraulic fluid to be directed thereto either through port 40 or port 42 to actuate linkage mechanism 32. As best shown in FIG. 2, when the actuating fluid enters chamber 44 through port 42, piston 36 moves leftwardly to move linkage mechanism 32 to its blade fold position and, when actuating fluid enters chamber 46 through port 40, it moves piston 36 to the right, to unfold the blade 16 and return it to its normal operation position. Spacer 48 is positioned in cylinder 38 and is of selected width W to serve as a positive stop for piston 36 when the blades are in their fully folded position. Spacers of selected width W may be used to vary piston 36 stroke.

Piston rod 50 connects through spherical clevis joint 52 to one end of link member 54, while the other end of link 54 connects through spherical clevis joint 56 to one of the three corners of triangular link 58. A second corner of triangular link 58 is pivotally connected at pivot joint 60 to sleeve 22. Link 58 is connected at its third corner at pivot joint 62 to twin link members 64, which are pivotally connected at their other ends at pivot connection 66 to fold bracket 70, which is, in turn, connected to fold hinge 15 through bolt members 73.

It will be noted, as best shown in FIG. 1, the joints 66, 62 and 60 form a triangle when the blade is in its operative, nonfolded position with the interconnected pivot joint 62 closest to hub 12, and with one corner 60 of the triangle connected to the hub, while the other corner 66 of the triangle is connected to the fold bracket 70 in turn to fold hinge 15 and to blade 16.

When blade 16 is in its operating position shown in FIGS. 1 and 2, flanges 72 of sleeve 22 engage flanges 74 of fold hinge 15 so that a single lock pin 76 can pass through aligned apertures in these flanges to lock blade

16 and fold hinge 15 in its unfolded or operable FIGS. 1 and 2 position. Pin 76 can be withdrawn from inner flanges of 72-74 by any conventional mechanism such as conventional solenoid 79 to permit blade folding. 5 This is the first step in the blade folding operation. Thereafter, actuating fluid is caused to enter chamber 44 to move piston 36 leftwardly and thereby cause piston rod 50 to move link 54 leftwardly. As best shown in FIG. 1, this leftward movement of piston 36 causes 10 axis 86 to move along arc or action line 88, thereby causing axis 82 to move along action line 84, and axis 78 to move along action line 80, while pivot joint 60 causes link 58 to pivot about pivot axis 90. As this motion continues, the link mechanism 32 passes through 15 a position in which pivot axes 78, 82 and 90 are in alignment. With these axes in alignment, the blade has folded slightly beyond its intended fully folded position. As this motion continues, links 58 and 64 assume the 20 over-center condition shown in FIG. 3, thereby returning and locking blade 16 in its fully folded position even when hydraulic fluid is removed from piston-cylinder arrangement 34. Over-center spring 92, which extends between fold bracket 70 and link 58 serves to retain links 58 and 64 in their over-centered, locked position. 25 Over-centering the links tends to put a tension load on piston 36, reacted by spacer 48 when blade wind forces is in the unfold direction. Fold links 58 and 64 move from the over-center condition to a straight line condition when blade wind force is in a fold direction. This provides tension on links 64 and 50. Spring 92, being preloaded in tension, tends to return blade to its over-center condition when wind force in fold direction slackens.

It will accordingly be seen that links 58 and 64 coact, 30 when powered by power piston 34, to both fold and lock blade 16 in its folded position with respect to hub 12.

Link 58 is made triangular in shape so that the most 35 effective moment arms of point 86 about axis 60, and point 82 about axis 80 may be achieved to overcome the blade folding loads in their most severe fold angle condition. The added advantage is in providing a smaller stroke of piston 36, reducing the required 40 length of the sleeve, and reducing packaging requirements.

Shim 94, of selected thickness, may be positioned between fold bracket 70 and the remainder of blade 16 so as to selectively control or adjust the final angle to 45 which link mechanism 32 causes blade 16 to fold with respect to hub 12.

It will also be noted by viewing FIG. 1 that while the 50 line of action between link 54 and the pivot connections 90 and 78 of links 58 and 64 are of selected dimension when the blade is in its FIG. 1 operative, unfolded position, this distance increases as the links fold toward their FIG. 3 positions so as to provide the most effective moment possible when the blade folding and unfolding loads are maximum during the folding and unfolding operation.

By viewing FIGS. 1 and 3, it will be seen that due to the motion of link mechanism 30, when actuated by power piston-cylinder arrangement 34, blade 16 is actuated between its FIG. 1 operable position to its FIG. 3 fully loaded position, having folded through a number of degrees represented by angle A. It will be obvious to those skilled in the art that by control of the stroke of piston 36, the length of the various links in link mecha-

nism 30, and shimming at 94, the angle through which the blade is caused to fold may be varied.

It will therefore be seen that my construction teaches a linkage mechanism which is power actuated to not only cause a helicopter blade to fold with respect to the hub a selected angular amount but also to be locked in the precise desired position when fully folded.

I wish it to be understood that I do not desire to be limited to the exact details of construction shown and described, for obvious modifications will occur to a person skilled in the art.

I claim:

1. A helicopter rotor having:

- A. a hub,
- B. a blade pivotally connected to said hub in blade fold relationship,
- C. means to fold said blade with respect to said hub and to lock said blade in a folded position including:
  - 1. two pivotally connected links of selected length and orientation so that the link free ends form a triangle with their interconnected ends so oriented that their interconnected ends are on the hub side of a line passing between the link free ends,
  - 2. means pivotally connecting the free end of one of said links to said hub,
  - 3. means pivotally connecting the free end of the other of said links to the foldable blade, and
  - 4. power means connected to force said pivotally interconnected link ends to the line extending between the pivot connections of said links to said hub and to said blade to thereby cause said blade to fold with respect to said hub, and to a position therebeyond so that said links are in over-center relationship to lock said blade in said folded condition.

2. A helicopter rotor according to claim 1 wherein said power means includes a powered cylinder-piston mechanism connected to said blade fold means so that motion of said piston within said cylinder causes pivot motion of said links.

3. A helicopter rotor according to claim 2 and including means to control the stroke of said piston and hence the angle of folding of said blade.

4. A rotor according to claim 3 and including a link member pivotally connected to said piston at one of its ends and pivotally connected to said link interconnected ends at its other end.

5. A rotor according to claim 1 and including means operatively connected to said blade fold means to vary the angle through which said blade is folded.

6. A rotor according to claim 1 wherein said blade is pivotally connected to said hub by means of a blade fold pin whose axis is selectively oriented so as to form a preselected angle in relation to the blade feathering axis to control the path of folded motion of the blade in its finally fully folded position and which also forms a selected angle relative to the rotor plane of rotation to provide adequate ground clearance for the blade during the folding motion.

7. A rotor according to claim 6 wherein the distance between the lines of force between said power means and said link pivot connections to said hub and said

blade increase as the blade is so powered to a folded position so as to create maximum moments at the location of maximum blade resistance to folding.

5 8. A rotor according to claim 1 wherein one of said links is substantially triangular in shape with one corner thereof pivotally connected to the other link, with a second corner thereof pivotally connected to the hub or blade and with the third corner thereof pivotally connected to the power means.

9. A rotor according to claim 1 and including an over-center spring connected between said blade and one of said links to restrain said links in the over-center relationship.

10. A rotor according to claim 1 and including single pin means to lock said blade to said hub when the blade is in its operable position.

11. A rotor according to claim 2 including means to control the stroke of said piston, and means to vary the angle of blade fold for the controlled piston stroke.

12. A helicopter rotor including:

- A. a hub,
- B. a blade connected to said hub for folding motion with respect thereto,

C. blade folding and locking mechanism including:

- 1. a first link member of substantially triangular shape pivotally connected to said hub at one of its corners,

20 2. a second link member pivotally connected to said blade at one of its ends and pivotally connected to the second corner of said first link and being of selected length and orientation so that the pivotal interconnection between the first and second links is on the hub side of a line extending between the pivotal connection between the first link and the hub and the second link and the blade,

3. a third link member pivotally connected to the third corner of said first link member,

4. a power cylinder-piston arrangement having:

- a. a cylinder,
- b. a piston mounted in said cylinder for reciprocation with respect thereto,
- c. a connecting rod connected to said piston and pivotally connected at its opposite end to the other end of said third link,

45 so that as said piston moves within said power piston-cylinder arrangement, said third link will cause the pivot interconnection between said first and second links to move into alignment with the pivot interconnection between said first link and said hub and said second link and said blade so as to cause the blade to fold with respect to the hub to a position beyond its normal fully folded position, and then to cause said pivotal interconnection between said first and second links to move to a position therebeyond to establish an over-center relationship therebetween to return the blade to its fully folded position and to so lock the blade so positioned.

13. Apparatus according to claim 12 and including 50 means to control the stroke of the piston.

14. Apparatus according to claim 13 and including means to vary the angular folding motion of said blade for a piston stroke so controlled.
